SHUTTLE MOTION FOR NARROW FABRIC LOOMS

George Holden, Philadelphia, Pa., assignor of one-third to Jules Bloch and one-third to John E. Fite, Jr., both of Philadelphia, Pa.

Application January 31, 1940, Serial No. 316,666

13 Claims. (Cl. 139—22)

This invention relates primarily to shuttle motions for narrow fabric looms, especially those of the multiple deck type, i. e. a loom adapted for simultaneously weaving a plurality of separate strips of tape, ribbon, etc., at one time without connecting the strips together in any way, or with the strips connected together at relatively spaced points along their lengths, such as in ladder tapes for Venetian blinds having cross straps interwoven at their opposite ends with the side tapes, or ordinance belts with cartridge loops or pockets interwoven with the belt, or numerous other articles of these same general characteristics.

In the case of weaving Venetian blind tapes of the kind noted above, four strips are woven separately at the same time to produce two side tapes and two cross straps, requiring the use of four separate shuttles for laying separate weft threads in four open warp sheds respectively and at predetermined times the shedding mechanism is operated to combine the warps of the cross straps with the warps of the side tapes for interweaving the ends of the cross straps with the side tapes at predetermined intervals.

The object of the present invention is to provide a simple highly efficient means for actuating the shuttles, as will be fully disclosed hereinafter, reference being had to the accompanying drawings of which:

Fig. 1 is a fragmentary side or end elevation of sufficient of a tape loom to illustrate the present invention as applied thereto;

Fig. 2 is a rear elevation of that end of the loom shown in Fig. 1;

Fig. 3 is a perspective view of the take-off guide for the finished tape;

Fig. 4 is an enlarged fragmentary front elevation of one section of the lay;

Fig. 5 is a vertical section taken on the line 5—5, Fig. 4;

Fig. 6 is a horizontal section taken on the line 6—6, Fig. 4;

Fig. 7 is a rear elevation of the lay section shown in Fig. 4;

Fig. 8 is a vertical section taken on the line 8—8, Fig. 7;

Fig. 9 is a vertical section taken on the line 9—9, Fig. 4;

Fig. 10 is a vertical section taken on the line 10—10, Fig. 4, with one of the shuttle guide tier frames swung outwardly into shuttle changing position;

Figs. 11 and 12 illustrate a Venetian blind tape in front and side elevation respectively in col-

lapsed form as it comes from the loom after weaving;

Fig. 13 shows the tape opened up subsequent to finishing after weaving by cutting short extensions of the cross tapes or straps which connect the two main tapes and hold the same in close parallel relationship during and after weaving;

Fig. 14 is a fragmentary rear view of one end of the lay beam, showing a modification of the invention;

Fig. 15 is a transverse sectional elevation taken on the line 15—15, Fig. 14; and

Fig. 16 is a sectional view of a detail of the structure shown in Fig. 14.

Ladder tapes for Venetian blinds normally consist of two main tapes A and B, see Fig. 13, spaced apart a distance equal to the width of the slats of the Venetian blind and connected by cross straps C and D upon which the slats are supported. The straps C and D are relatively narrow, as compared to the tapes A and B and are disposed alternately at opposite sides of the center line of the complete ladder tape, as shown in Fig. 11. In some ladder tapes the cross straps C and D and the main tapes A and B are woven separately, short lengths of the strap tapes C and D being subsequently sewn at their opposite ends to the main tapes A and B respectively. In other instances, the tapes A, B, C and D are woven simultaneously but the methods prior to the present invention involved considerable waste of material. For example, intermediate lengths of the warp yarns, after weaving of the tapes, were severed at the points where the one end of one cross strap C, for example, was woven in with the strap A and the points where the next cross strap of that series was woven in with the strap B.

The present invention is directed to elimination of this waste and to that end the straps C are interwoven with the straps A, as indicated at *a* and then immediately interwoven with the straps B, as indicated at *b*, leaving a very short length of the strap indicated at *c* in Fig. 12 connecting the interwoven portions *a* and *b*. When completed, these small connecting portions *c* are severed intermediate the main straps A and B permitting the main straps A and B to be spaced apart laterally, as indicated in Fig. 13. In a like manner the straps D are interwoven with the main tapes A and B, as indicated at *a* and *b*, with small connecting portions *d* which are severed in the same manner as the connecting portions *c*, as noted above. The completed tape of Fig. 13 therefore, is substantially the same as any other Venetian blind ladder tape where the main

tapes and cross straps are woven simultaneously, with the exception that the waste of the material as previously noted, has been eliminated.

The method involved is that the two main tapes A and B are woven simultaneously in spaced relation to each other and at the same time the cross tapes or straps C and D are being woven intermediate the main tapes A and B, each cross strap being interwoven with one main tape at relatively spaced intervals along said main tape and with the second main tape immediately following the weaving of the cross strap with the first main tape, providing the relatively small or short severing sections directly connecting the two main tapes, with the interweavings of the two series of cross straps arranged in staggered alternating relation to each other.

The apparatus employed for weaving the tape primarily consists of improvements to a conventional tape loom. In the present instance, instead of the lay beam 1 of the loom being pivotally mounted for oscillation between the fell 2 and the harness frames 3, the lay 1 is provided with flanged wheels 4, 4 which are adapted to ride on tracks 5 carried by fixed horizontal portions of the cross frames 6 of the loom. The lay 1, as usual, is connected by pitmans 7 to the usual cranks 8 of the main crank shaft 9 of the loom, whereby rotation of the crank shaft 9 produces horizontal straight line reciprocation of the lay 1.

Secured to the lay 1 (see Fig. 4) is a plurality of vertically arranged banks or tiers 10 of shuttle guides 11, 11 forming horizontal T slots 12, 12 in which are slidably mounted shuttles 13, 14, 15, and 16. The tiers 10, 10 are spaced apart longitudinally of the lay 1 to provide work spaces 17 between the tiers 10 of each adjacent pair thereof.

The main tape A is composed of two series of warp threads A1 and A2 respectively (see Figs. 1 and 5) controlled by harness frames 18 and 19 which diverge rearwardly from the fell 2 to form an open warp shed A3, through which the shuttle 13 moves from its guide 12 in one tier 10 to a corresponding guide groove 12, in an adjacent tier 10, across the work space 17 between said tiers, through which the warp series A1 and A2 pass. Obviously, when the shuttle 13 moves in one direction across the space 17, it lays a weft thread between the warp series A1 and A2, whereupon the harness frames 18 and 19 reverse their respective positions, and consequently the threads A1 and A2 respectively, to form a new shed A3 for the passage of the shuttle 13 in the opposite direction. During the interval of the change in the warp shed the lay 1 moves toward the fell 2 and a reed comb 17a disposed in the space 17 behind the shuttle guide tiers 10, 10 beats the weft thread up to the fell 2, whereupon the lay 1 moves in the opposite direction.

In a like manner the main tape B is composed of warp series B1 and B2 controlled by heddle frames 20 and 21 respectively, which reverse their position after each beat-up of the lay to form warp sheds B3 through which the shuttle 16 passes from one tier of shuttle guides to the next adjacent tier, for laying its weft thread in the open warp shed B2 between the beat-up motions of the lay. The mechanism is so arranged that the reciprocations of the shuttles 13 and 16 are simultaneous but in opposite directions, the movement of the shuttle to the right, for example, being counteracted by movement of the shuttle 16 to the left and vice versa.

The cross tapes C are formed of warp series C1

and C2 controlled by heddle frames 22 and 23 respectively, which reverse their positions to form open warp sheds C3 through which the shuttle 14 moves concurrently with the shuttle 13, the heddle frames 18 and 22 moving concurrently, for example, upwardly to lift the warps A1 and C1 respectively, while the warp frames 19 and 23 move downwardly to carry the warps A2 and C2 downwardly and vice versa.

The cross straps D, in a like manner, are formed of warp series D1 and D2 controlled by heddle frames 24 and 25 respectively to form the warp shed D3 through which the shuttle 15 moves concurrently with the shuttle 16, the warp heddle frames 24 and 25 reversing their positions concurrently with the warp heddle frames 20 and 21 which control the warp series B1 and B2 of the main tape B.

During the course of weaving, each of the independent pairs of warp series and the shuttles operating through the warp sheds respectively formed thereby, are operated to form the four independent strips of tape, i. e. the main tapes A and B and the cross straps C and D respectively.

At a predetermined point in the weaving cycle, the heddle frames 22 and 23 are raised until the warps C1 and C2 coincide with the warps A1 and A2 and thereafter, for relatively short periods of weaving, the frames 18 and 22 move exactly the same, while the heddle frames 19 and 23 likewise move exactly the same in reversing their positions with the heddle frames 18 and 19; and the shuttle 13 moves across the combined warp shed formed by the warps A1 and C1 on one side and the warps A2 and C2 on the other side of the open warp shed to lay its weft thread therein, by which the warps A1—C1 are coincidentally woven together while the warps A2 and C2 are simultaneously coincidentally woven into the fabric, thus producing the interwoven areas *a* appearing in Fig. 11. During this short period of weaving the shuttle 14 reciprocates idly, there being no warp shed at that time for the shuttle 14 to pass through.

When the interweaving of the straps C with the main tapes A in the areas *a*, is completed the heddle frames 22 and 23 controlling the warps C1 and C2 drop from their positions above noted to corresponding positions in relation to the heddle frames 20 and 21, which control the warps B1 and B2 of the second main tape B, and wherein the warps C1 coincide with the warps B1 and the warps C2 coincide with the warps B2 to form a combined open shed through which the shuttle 16 operates. The heddle frames 22 and 20 then move concurrently in opposed relation to the heddle frames 23 and 21 to raise and lower the warps B1—C1 and B2—C2 to form open warp sheds for the passage of the shuttle 16 for laying its weft thread between the changing warps and thereby produce the interwoven areas *b*, wherein the second ends of the strap members C are interwoven with the main tapes B in the areas *b*. The shuttle 14 still operates idly.

As a result of the dropping of the heddle frames 22 and 23 from their positions coinciding with the heddle frames 18 and 19 to their positions coinciding with the heddle frames 20 and 21, the short severing sections *c*, composed solely of the warp threads C1 and C2, are formed.

When the interweaving of the section *b* is completed the heddle frames 22 and 23 are again raised to their normal weaving positions, wherein the warps C1 and C2 are again operated to form warp sheds C3 for passage of the shuttle 14 and

the resulting weaving of the main portions of the straps C, which extend from the main tape B to the main tape A; and the weaving continues until it is again time to weave one of the interwoven areas *a*, after which the cycle of weaving just described, is repeated.

During this time the heddle frames 24 and 25 have been operating in a regular manner to form the warp sheds D3 between the warps D1 and D2 and the shuttle 15 has been moving alternately in opposite directions across the work space 17 and producing the main portion of one of the straps D, which extends from the tape B to the tape A. After a sufficient length of the strap D is formed in this manner the warp heddle frames 24 and 25 are raised to positions coinciding with the heddle frames 18 and 19 and thereafter operate concurrently therewith and with the shuttle 13 to interweave the strap D with the strap A in the same manner as hereinbefore described with respect to the strap C and by which the interwoven area *a* is produced, the shuttle 15 in the meantime operating idly, as noted above, in regard to the shuttle 14.

The heddle frames 24 and 25 then drop to positions coinciding with positions of the heddle frames 20 and 21 respectively and thereafter cooperate coordinately with the heddle frames 20 and 21 and the shuttle 16 to produce the interwoven areas *b*, the drop from the upper position coinciding with the heddle frames 18 and 19 to the lower position coinciding with the heddle frames 20 and 21, producing the short severing section *d*. After the interwoven area *b* is completed, during which the shuttle 15 is operating idly, the heddle frames 24 and 25 return to their normal position with respect to the shuttle 15 and cooperate with the movements thereof to produce the main body portion of the next cross strap D.

The above noted cycles of weaving are alternately carried out to produce alternately the straps C and D and to interweave these straps with the main tapes A and B in the areas *a* and *a* and *b* and *b* with the severing areas *c* and *d* therebetween.

As shown in Fig. 3 the fell 2 is formed at the rear end of a tape guide 26, which is secured to and projects rearwardly from the breast beam 27 of the tape loom, with the warp series A1, A2, C1, C2, D1, D2, B1 and B2 diverging from a slot 28 formed in the rear end of the guide 26 at the very mouth of which the fell 2 is formed, the finished fabric F, composed of the main tapes A and B and interwoven cross straps C and D passing forwardly through a channel 29 formed in the guide 26.

As shown in Figs. 5, 6, 7, 8, 9 and 10, each of the shuttles 13, 14, 15 and 16 is provided with grooves 30 and 31 which cooperate with the guides 11, 11, to slidably support the shuttles. Each shuttle is provided with a gear rack 32 (see Fig. 6) by which the shuttle is moved in the guides 11 from one tier 10 to the adjacent tier 10. Cooperating with each of the tiers are vertical shafts 34 and 35 (see Figs. 2, 7 and 8) which are coaxially aligned and rotatably mounted in bearings 36, 37 and 38 (see Fig. 8), carried by the lay 1. The shaft 34, in each instance, is provided with gears 39 and 40 which intermesh with the teeth 32 of the shuttles 13 and 14 respectively. The shaft 35 in each instance, is provided with gears 41 and 42 which mesh with the teeth 32 of the shuttles 15 and 16 respectively. The shaft 34

is provided with a third gear 43 which meshes with a gear rack 44 slidably mounted in the upper portion of the lay 1, while the shaft 35 is provided with a gear 45 which meshes with a gear rack 46 slidably mounted in the lower portion of the lay 1.

The gear racks 44 and 46 (see Fig. 2) are provided with pins 47 and 48 which ride in slots 49 and 50 formed in oppositely extending aligned arms 51a, 51b, of a four arm lever 51. The cross-arm lever 51 is pivotally mounted at 52 on a bracket 53 carried by the lay 1, the slots 49 and 50 being formed in diametrically opposite arms of the cross member 51. The two arms 51c, 51d, of the cross member 51, are disposed at right angles to the arms 51a, 51b in which the slots 49 and 50 are formed, and are connected to the ends of flexible elements such as straps 54 and 55 respectively. The straps 54 and 55 pass around a guide roller or rollers 56 and are connected to cranks 57 and 58 on a crank shaft 59.

The crank shaft 59 (see Fig. 1) is provided with an elliptical gear 60 which meshes with an eccentric gear 61 secured to the main crank shaft 9 of the machine, so that during the approach, through, and for a short period after the precise dead center positions of the crank shaft 9 and the directional change points in the reciprocations of the lay 1, the crank shaft 59 is operated at increased speed to effect movement of the shuttles 13-14 in one direction and the shuttles 15 and 16 in the opposite direction, with the lay in the back position, the cranks 57 and 58 through the straps 54 and 55 effecting rocking of the cross 51 by which movement of the shuttle driving racks 44 and 46 in opposite directions simultaneously, is effected.

During the dead center position of the crank shaft 9 with the lay 1 in the forward position, 40 and the reed combs 17a beating the inlaid wefts up at the fell 2, the heddle frames 18 to 25 inclusive, are operated to change the positions of the several warp series forming the open warp sheds 45 for the passage of the shuttles 13, 14, 15 and 16 when the lay 1 again moves to the back dead center position of the crank shaft 9.

Any suitable dobby or jacquard mechanism or a head and box motion of the Crompton-Knowles type may be provided for raising and lowering 50 the heddle frames in their changes of position to effect formation of the open warp sheds.

The loom of the present case, like other narrow fabric looms or tape looms, is capable of producing a number of strips of finished product simultaneously, for example, twenty strips at one time; and as a result of this there is no spare room between the strips through which the shuttles 60 may be removed from their guides when the bobbin of a shuttle is exhausted. In ordinary single deck tape looms this produces no inconvenience. However, in this four-deck machine, where there are four shuttles disposed one above the other, it is impossible to take out a shuttle in the ordinary manner, therefore, as shown in Fig. 10, each tier 10 of the shuttle guides 11, 11 is mounted as a unit on carrier bars 70, 70. Each tier unit 10 is pivotally mounted at 71 to the upper portion of the lay 1 and is held in position by a spring latch 72 cooperating with a keeper 73 on the lower portion of the lay 1. By raising the latch 72 the tier 10 may be swung about its pivot 71 to a position above the uppermost warps A1, wherein anyone of the shuttles 13, 14, 15 and 16 may be readily removed from its guide and a

full-bobbin shuttle replaced therein. In swinging one of the tiers 10, with the pair 13-14 or 15-16 of shuttles therein, as noted, the gear racks 32 of the shuttles are disengaged from their operating gears 39 and 40 or 41 and 42, as the case may be. In returning the tier with its replenished shuttles to normal position in the lay 1, the teeth of the gear racks in the shuttles automatically intermesh with the driving gears and are held in operating relation thereto by the latch and keeper 12-13.

The bearings 36, 36 for the upper ends of the upper shuttle driving shafts 34 are secured to the upper rail 75 of the lay 1, while the bearings 38 for the lower ends of the lower shuttle drive shafts 35 are secured to the lower rail 76 of the lay. The rails 75 and 76 are secured to and carried by upright brackets 77, 77 (see Figs. 7 and 9). These vertical brackets are secured to and extend vertically from the main beam 78 of the lay. The bearings 37 for the lower ends of the upper shuttle drive shafts 34 and for the upper ends of the lower shuttle drive shafts 35 are carried by cross brackets 79 secured to the upright brackets 77.

The beat-up combs 17a are held in the lay 1, at their upper ends, in sockets 80 formed by cap plates 81 secured to the upper rail 75 (see Fig. 5) the rear face of the rail 75 and the ends of the bearings 36, 36; and at their lower ends in sockets 82 formed by blocks 83, secured to the main beam 78, the rear face of the rail 76, and the ends of the bearings 38, 38.

The shuttle driving racks 44 and 46 are operatively held for sliding movement in their guide grooves 85 and 86 in the rails 75 and 76 by the vertical brackets 77, 77 (see Fig. 9).

The carrier bars 70, 70 for each tier of shuttle guide blocks 11, 11, are located at the opposite ends respectively of the blocks and the rear faces of the blocks, intermediate the carrier bars 70, 70, bear against the front faces of the upright brackets 77 and are steadied in the lay 1 thereby. (See Figs. 4, 7 and 9.)

In order to reduce the lift of the warps to a minimum in forming the open warp sheds A3, B3, C3, and D3, the two middle shuttles 14 and 15 in each set are straight, i. e. the central plane of each thereof is perpendicular to the common plane of the faces of the guide blocks 11, 11, but the two outermost shuttles, 13 and 16, are bent, toward each other, i. e. their respective central planes extend at convergent angles with respect to the common plane of the front faces of the guide blocks 11, 11.

The type of fabric in the tapes may be of a plain one-over-one weave, as described above, or any other twill or patterned type, as desired, and depending upon the shedding mechanism used. For twills or other patterns one or more additional heddle frames and warp series controlled thereby may be used, as indicated in Fig. 1, for example, wherein additional warps A4 and B4 are shown under control of extra heddle frames for cooperation with the warps A1, A2 and B1, B2 in the weaving of the main tapes A and B respectively.

It will be noted that during the greater portion of the weaving of the fabric F there are four separate strips A, B, C, D, in different vertically spaced levels respectively being woven simultaneously. Under such circumstances an ordinary oscillating lay would tend to beat up the lower strips tighter than the upper strips. With all four strips being integrally interwoven at spaced

points to form the complete ladder tape it is essential that all four strips be beaten up to exactly the same extent, otherwise one side of the ladder tape would be longer than the other causing the slats of the Venetian blind to hang unevenly. The exact uniformity of beat up is efficiently accomplished by the straight line reciprocatory movement of the lay 1, in the present instance.

As previously noted, when the cross straps and side tapes of a Venetian blind ladder are being interwoven by the shuttle 13 or the shuttle 16, as the case may be, the shuttle 14 or the shuttle 15, depending upon which cross strap C or D is being interwoven with which side tape A or B, reciprocates idly across the work space 17 between adjacent shuttle guides 11, 11. It may be desirable to eliminate such idle movements of the shuttles 14 and 15 under such circumstances or, in cases where the loom is weaving two or three separate straps of fabric which are not to be connected to any place along their respective lengths, it would be desirable to retain the shuttles for the idle deck or decks of the loom at an inoperative position. In such cases the structure shown in Figs. 14, 15 and 16 may be employed to place and retain the shuttles 14 and 15, or either thereof, out of action.

As shown in Figs. 14 and 15 the rails 75a and 76a of the lay 1a are provided with wide grooves 85a and 86a respectively. Slidably mounted in the guide grooves 85a is a pair of shuttle driving racks 44a and 44b, and in the groove 86a is slidably mounted a pair of shuttle driving racks 46a and 46b. The rack 44a meshes with gears 43a secured to the upper ends of shafts 34a. Each of the shafts 34a is provided with a gear 40a for driving a shuttle 14a, which is one of the two central shuttles in each vertical series thereof. The second central shuttle 15a of each vertical series is driven by a gear 41a secured to a shaft 35a which also carries a gear 45a which meshes with the gear rack 46a in the lower lay rail 76a.

Rotatably mounted on the shaft 34a is a sleeve shaft 34b and rotatably mounted on the shaft 35a is a sleeve shaft 35b. On the upper end of the sleeve shaft 34b is a gear 43b which meshes with the shuttle driving rack 44b. On the opposite end of the sleeve shaft 34b is a gear 40b, which drives the uppermost shuttle 13a of each vertical series. The lowermost shuttle 16a of each vertical series is driven by a gear 41b secured to one end of the sleeve shaft 35b, the lower end of said sleeve shaft being provided with a gear 45b which meshes with the teeth of the shuttle driving rack 46b.

The motion for reciprocating the racks 44a, 44b, 46a, 46b, is the same as previously described. The driving rack 44b is provided with a drive pin 47b with which the cross-arm-lever 51 cooperates to effect longitudinal reciprocation of the driving rack 44b. The driving rack 46b is provided with a drive pin 48b, which likewise cooperates with the cross-arm-lever 51 for receiving its longitudinal reciprocation.

Normally, the racks 44a and 44b move in unison in one direction while the racks 46a and 46b move in unison in the opposite direction and for this purpose said pairs of racks are adapted to be locked or coupled together by any suitable means such, for example, as that shown in Fig. 16, wherein one of the driving racks is provided with a bushed opening 90 for the reception of one end of a coupling pin 91. The coupling pin

91 is slidably mounted in a bushed opening 92 formed in the other rack of the pair.

The coupling pin 91 may be provided with a collar 93 between which and a bearing 94, formed at one end of a housing 95 and constituting an extended bearing for the coupling pin 91, is a spring 96. The spring 96 tends to force the coupling pin 91 into the bushing 90 at all times to lock the two racks together.

The coupling pin 91 may be provided with a head 97 for connecting the pin to the dobby, jacquard, or head motion by which the heddle frames of the loom are selectively raised and lowered for changing the warp sheds through which the various shuttles pass, whereby, at predetermined times and for predetermined periods of time, the coupling pins 91 may be withdrawn from the bushed holes 90, leaving the rack 44a or 46a, as the case may be, standing in an idle position while the other rack of each pair, i. e. the rack 44b or 46b, continues to reciprocate and operate the shuttles 13a and 16a while the shuttles 14a and/or 15a remain idle.

In one instance the head 97 and its coupling pin 91 are connected directly by a wire 98 to the shed forming mechanism. In the other instance the wire 98 is connected through a lever 99 to the head 97 of the coupling pin 91. In either instance, with the wires 98, 98 connected to levers or other operating parts of the shedding motion, in the same manner as the heddle frames 18 to 25 are respectively connected to the shedding mechanism, the wires 98, 98 are operated by the shedding mechanism to withdraw the coupling pin 91, 91 at predetermined times and to hold said pins in such withdrawn positions for predetermined periods of time to disconnect the racks for the center shuttles from the mechanism, by which these racks are reciprocated. Obviously, the coupling pins 91 may be selectively operated by the shedding mechanism to hold one in a withdrawn position while the other is in a coupling position or vice versa, or both pins may be withdrawn and withheld simultaneously for corresponding periods of time, in the same manner as the heddle frames are raised and lowered selectively and held in raised or lowered positions for any length of time desired by the shedding mechanism which forms no part of the present invention and being of standard well-known type no further explanation or description thereof is deemed necessary as it is believed that the necessary connections may be readily made by anyone familiar with the art.

By the above arrangement either one or both of the center shuttles 14a and 15a may be held out of action during weaving of the cross straps C or D with the main tapes A or B at such times as these center shuttles would normally reciprocate idly, or one or the other or both of these center shuttles may be held out of action at any time when separate strips are being woven by the shuttles 13a and 16a respectively.

I claim:

1. In a loom, a lay, vertically spaced horizontal guides pivotally supported by said lay, shuttles reciprocably mounted in said guides, vertical shafts rotatably mounted on said lay, and gears on said shafts adapted to intermesh with gear racks on said shuttles for reciprocating said shuttles in said guides, with one series of said shafts operating one series of said shuttles and a second series of said shafts operating a second series of said shuttles.

2. In a loom, a lay, vertically spaced horizontal

guides pivotally supported on said lay, shuttles reciprocably mounted in said guides, vertical shafts rotatably mounted on said lay, and gears on said shafts adapted to intermesh with gear racks on said shuttles for reciprocating said shuttles in said guides, with one series of said shafts operating one series of said shuttles and a second series of said shafts operating a second series of said shuttles in opposite directions to the first

10 said series of shuttles.

3. In a loom, a lay, vertically spaced horizontal guides pivotally supported on said lay, shuttles reciprocably mounted in said guides, vertical shafts rotatably mounted on said lay, gears on 15 said shafts adapted to intermesh with gear racks on said shuttles for reciprocating said shuttles in said guides, with one series of said shafts operating one series of said shuttles and a second series of said shafts operating a second series of said shuttles, a pair of gear racks reciprocably mounted on said lay and meshing with gears on said shafts for actuating said shafts, and means for reciprocating said gear racks.

4. In a loom, a lay, vertically spaced horizontal 25 guides pivotally supported on said lay, shuttles reciprocably mounted in said guides, vertical shafts rotatably mounted on said lay, gears on said shafts adapted to intermesh with gear racks on said shuttles for reciprocating said shuttles in said guides, with one series of said shafts operating one series of said shuttles and a second series of said shafts operating a second series of said shuttles, a pair of gear racks reciprocably mounted on said lay and meshing with gears on 30 said shafts for actuating said shafts, and means for reciprocating said gear racks carried by said lay.

5. In a loom, a lay, vertically spaced horizontal 35 guides pivotally supported on said lay, shuttles reciprocably mounted in said guides, vertical shafts rotatably mounted on said lay, gears on said shafts adapted to intermesh with gear racks on said shuttles for reciprocating said shuttles in said guides, with one series of said shafts operating one series of said shuttles and a second series of said shafts operating a second series of said shuttles in opposite directions to the first said 40 series of shuttles, a pair of gear racks reciprocably mounted on said lay and meshing with gears on said shafts for actuating said shafts, and means for reciprocating said gear racks carried by said lay.

6. In a loom, a lay, vertically spaced horizontal 45 guides pivotally supported on said lay, shuttles reciprocably mounted in said guides, vertical shafts rotatably mounted on said lay, gears on said shafts adapted to intermesh with gear racks on said shuttles for reciprocating said shuttles in said guides, with one series of said shafts operating one series of said shuttles and a second series of said shafts operating a second series of said shuttles in opposite directions to the first said series of shuttles, a pair of gear racks reciprocably mounted on said lay and meshing with gears on 50 said shafts for actuating said shafts, and means for reciprocating said gear racks carried by said lay.

7. In a loom, a lay, vertically spaced horizontal

55 guides pivotally supported on said lay, shuttles reciprocably mounted in said guides, vertical shafts rotatably mounted on said lay, gears on said shafts adapted to intermesh with gear racks on said shuttles for reciprocating said shuttles in said guides, with one series of said shafts operating one series of said shuttles and a second series of said shafts operating a second series of said shuttles in opposite directions to the first said series of shuttles, a pair of gear racks reciprocably mounted on said lay and meshing with gears on said shafts for actuating said shafts, means for reciprocating said gear racks carried by said lay, and means independent of said lay for actuating said rack-reciprocating means.

70 8. In a loom, a lay, vertically spaced horizontal

ing one series of said shuttles and a second series of said shafts operating a second series of said shuttles in opposite directions to the first said series of shuttles, a pair of gear racks reciprocably mounted on said lay and meshing with gears on said shafts for actuating said shafts, means for reciprocating said gear racks carried by said lay, means independent of said lay for actuating said rack-reciprocating means, and flexible means operatively connecting said actuating means with said rack-reciprocating means.

8. In a loom, a lay, a plurality of laterally spaced vertical tiers of vertically spaced shuttle guides on said lay, means for pivotally attaching each tier to said lay in a manner to provide relative displacement of each tier from normal working position on said lay to a position affording ready interchangeability of the shuttles in the guides.

9. In a loom, a lay, a plurality of laterally spaced vertical tiers of vertically spaced shuttle guides on said lay, means for pivotally connecting the upper end of each tier to said lay, and means for detachably connecting the lower end of each tier to said lay.

10. In a loom, a lay, a plurality of laterally spaced vertical tiers of vertically spaced shuttle guides on said lay, means for pivotally connecting the upper end of each tier to said lay, and a spring latch detachably securing the lower end of each tier to the lay.

11. In a loom, a lay, vertically spaced horizontal guides pivotally supported on said lay, shuttles reciprocably mounted in said guides respectively, vertical shafts rotatably mounted on said lay adjacent said guides, a pair of gears on each shaft, a driving gear rack meshing with one of the gears each of a group of said shafts, a driving gear rack meshing with one of the gears of each of another group of said shafts, driven gear racks meshing respectively with the second gears on said shafts, means for reciprocating said driving gear racks, and means for coupling and uncoupling said driving gear racks selectively for concurrent or relative reciprocation.

12. In a loom, a lay, vertically spaced horizontal guides pivotally supported on said lay, shuttles reciprocably mounted in said guides respectively, vertical shafts rotatably mounted on said lay adjacent said guides, sleeves rotatably mounted on said shafts, a pair of gears on each shaft, a pair of gears on each sleeve, a driving gear rack cooperating with one of the gears on each shaft, a driving gear rack cooperating with one of the gears on each sleeve, driven gear racks on a group of said shuttles cooperating with the second gears on said shafts, driven gear racks on a second group of said shuttles cooperating with the second gears on said sleeves, means for reciprocating said driving gear racks, and means for coupling and uncoupling said driving gear racks selectively for concurrent or relative reciprocation.

13. In a loom, a lay, vertically spaced horizontal guides pivotally supported on said lay, shuttles reciprocably mounted in said guides respectively, a series of vertical shafts rotatably mounted in said lay adjacent said guides, a second series of vertical shafts respectively aligned axially with said first series, sleeves respectively mounted for rotation on said vertical shafts, a pair of gears on each shaft, a pair of gears on each sleeve, a driving gear rack cooperating with one gear on each shaft of one of said series, a driving gear rack cooperating with one gear on each shaft of the second series, a driving gear rack cooperating with one gear on each sleeve on the first series of shafts, a driving gear rack cooperating with one gear on each sleeve on the second series of shafts, driven gear racks on said shuttles for cooperation with the second gears on said shafts and sleeves, means for reciprocating said driving gear racks, and means for coupling and uncoupling pairs of said driving gear racks selectively for concurrent or relative reciprocation.

GEORGE HOLDEN.
